UNITED STATES PATENT OFFICE.

DAVID H. LEACH, OF SACRAMENTO, CALIFORNIA.

TROUSERS HANGER AND STRETCHER.

1,205,551.

Specification of Letters Patent. Patented Nov. 21, 1916.

Application filed February 19, 1916. Serial No. 79,382.

To all whom it may concern:

Be it known that I, DAVID H. LEACH, a citizen of the United States, residing at Sacramento, in the county of Sacramento and State of California, have invented certain new and useful Improvements in Trouser Hangers and Stretchers; and I do hereby declare the following to be a full, clear, and exact description of the invention, such as will enable others skilled in the art to which it appertains to make and use the same.

This invention relates to new and useful improvements in trousers hangers and stretchers and one of its objects is the provision of a device of this character, which shall be simple, durable and efficient, and which may be manufactured and sold at a comparatively low cost.

Another object of this invention is to provide a lower bar which has slidably mounted thereon an upper bar, which bars have secured thereto U-shaped members to receive the cuffs or the ends of a pair of trousers to support them in a suspended position to remove wrinkles or creases therefrom.

Another and more specific object of this invention is to provide a spring which is attached to one end of each of the bars to hold them in an extended position to stretch and securely hold the ends of the trousers to the U-shaped members.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a perspective view of a trousers hanger and stretcher constructed in accordance with my invention, illustrating in dotted lines the ends of a pair of trousers secured thereto, and Fig. 2 is a vertical sectional view illustrating one of the connections between the upper bar and the lower bar.

Referring in detail to the drawing, 1 indicates a lower bar, having its ends bent at right angles and extending upwardly therefrom to form stops 2 and 3. Slidable upon the bar 1 between the stops 2 and 3 is an

upper bar 4 and has secured to the under face a pair of clips 6 and 7. The clips 6 and 7 engage the bar 1 and slidably secure the bar 4 to the bar 1 for movement between the stops 2 and 3. The bar 4 is bent upwardly and downwardly upon itself intermediate its ends, to provide a finger grip 8 and which may receive a hook or support for supporting the device, which will be herein-after more fully described.

The top 3 is provided with an aperture 9 to which is secured one end of a coil spring 10 and the opposite end of the spring 10 is secured within an aperture 11 formed in the free end of the finger grip 8 to provide a tension means between the bars 1 and 4 to normally hold them in an extended position. Secured to the end 12 of the bar 4 and to the bar 1 adjacent the stop 2 is a pair of U-shaped members 13 and 14. The arms 15, 16, 17 and 18 of the U-shaped members extend downwardly and on each side of the bars 1 and 4 and each has mounted thereon rubber sleeves 19. The arms 16 and 18 are each placed within a cuff or end of a trousers leg 20 at the crease of the rear and front of the trousers leg and the arms 15 and 17 are each placed within the cuff or end of a trousers leg 21 at a point similar to the arms 16 and 18. The tension of the spring 10 upon the bars 1 and 4 will cause the arms 15, 16, 17 and 18 to stretch the trousers legs 20 and 21 and will prevent them from disengaging therefrom.

From the foregoing description taken in connection with the accompanying drawing, it will be seen by placing the index finger within the finger grip 8 and placing the palm of the same hand against the stop 2 and pulling upon the finger grip against the tension of the spring 10 the U-shaped members 13 and 14 will be moved in the direction of each other and a pair of trousers may be placed on or removed therefrom as desired. After a pair of trousers has been placed on the U-shaped members 13 and 14 by moving them in the direction of each other in the manner heretofore described the device may be hung on any suitable hook or support by passing it through the finger grip 8 and the trousers may be then held in a suspended position to remove all wrinkles and creases therefrom.

While I have shown and described the preferred embodiment of my invention, it will be understood that minor changes in

construction, combination and arrangement of parts may be made without departing from the spirit and scope of the invention as claimed.

5 Having thus described my invention, what I claim is:—

1. Trouser hanger and stretcher comprising a bar, said bar provided with its ends bent at right angles and extending upwardly therefrom to provide stops, a second bar slidably mounted upon first mentioned bar between said stops, means for slidably securing second mentioned bar to first mentioned bar, a U-shaped member secured to second mentioned bar and extending downwardly therefrom, a second U-shaped member secured to the first mentioned bar and extending downwardly therefrom, said U-shaped members adapted 10 to receive the ends of a pair of trousers, and means attached to one end of second mentioned bar and to one of said stops to hold said U-shaped members within the ends of the trousers.
2. Trouser hanger and stretcher comprising a lower bar, stops formed on each end of said lower bar, an upper bar slidable upon the lower bar between said stops, clips secured to the upper bar and adapted to engage the lower bar to slidably secure the lower bar to the upper bar, a U-shaped member secured to one end of the upper bar and extending downwardly on each side thereof, a second U-shaped member secured 15 to the lower bar adjacent one of the stops and extending downwardly therefrom and upon each side thereof, said U-shaped members inserted within the ends of a pair of trousers, and a coil spring secured to one 20 of the stops and to one end of the upper member to hold said upper member and lower member in an extended position to crease and secure the ends of the trousers to the U-shaped members.
3. Trouser hanger and stretcher comprising a lower bar, upwardly extending stops formed on each end of said bar, an upper bar slidable upon said lower bar between the stops, means for slidably securing 25 the upper bar to the lower bar to allow it to move between said stops, a U-shaped member secured to one end of the upper bar and

extending downwardly therefrom, a second U-shaped member secured to the lower bar adjacent the stop at one end thereof and extending downwardly therefrom, said U-shaped members adapted to receive the ends of a pair of trousers, said upper bar bent intermediate its ends in a direction upwardly and rearwardly upon itself to form a finger grip, and means attached to the end of the finger grip and to one of said stops to hold the bars in an extended position.

4. Trouser hanger and stretcher comprising a lower bar, stops formed on each end of said bar, an upper bar slidably mounted upon said lower bar and adapted to move in a space between said stops, means for slidably securing the upper bar to the lower bar, a U-shaped member secured to one end of the upper bar and extending downwardly therefrom, a second U-shaped member secured to the lower bar and extending downwardly therefrom, said U-shaped members adapted to receive the ends 70 of a pair of trousers, said upper bar bent intermediate its ends to form a finger grip, and a spring attached to said finger hold and to said stops to hold the bars in an extended position.

5. Trouser hanger and stretcher comprising a lower bar, stops formed on each end of said bar, clips slidably mounted on said bar, an upper bar secured to said clips and adapted to slide upon the lower bar between said lugs, a U-shaped member secured to one end of the upper bar, the opposite end of said upper bar bent upwardly and rearwardly upon itself to form a finger grip to receive a hook or support for suspending the device, a second U-shaped member secured to the lower bar and extending downwardly therefrom, said U-shaped members adapted to be inserted within the ends of a pair of trouser legs, and a spring connected 90 to the finger grip and to one of said stops to normally hold the bars in an extended position.

In testimony whereof I affix my signature in presence of two witnesses.

DAVID H. LEACH.
